UNITED STATES PATENT OFFICE.

JAMES J. LAWLER, OF PELHAM, NEW YORK.

URINAL.

1,101,703.

Specification of Letters Patent. Patented June 30, 1914.

Application filed March 31, 1913. Serial No. 757,749.

To all whom it may concern:

Be it known that I, JAMES J. LAWLER, a citizen of the United States, and resident of Pelham, in the county of Westchester and 5 State of New York, have invented certain new and useful Improvements in Urinals, of which the following is a specification.

This invention relates to urinals, and has for its object the production of a urinal 10 which is automatically flushed by the change in temperature of the water passing into and through the urinal.

I will premise my description by stating that urinals in public places, flushed automatically by timed devices waste considerable water for the reason that the urinals are flushed whether they have been used or not. Devices operated by hand are almost constantly ignored by users, as observations 20 clearly prove. To overcome these objections, I have produced a urinal which is automatic under all conditions, as will be seen in the operation hereinafter described.

Reference being had to the accompanied 25 drawings, Figure 1 is a side view, partly in section of a modern urinal, extending to the floor, to which my automatic flushing device is attached. Fig. 2 is a wall supported urinal, showing method of attaching, the 30 mechanism above the urinal (not shown) being similar to that shown in Fig. 1. Fig. 3 is a front elevation, enlarged, of the automatic flushing device, showing method of connecting up. Fig. 4 is a side elevation of Fig. 3. Fig. 5 is a side central sectional view of Fig. 4, and Fig. 6 is a front central sectional view of Fig. 3, the diaphragm chamber being partly broken away in elevation.

Similar reference characters denote like 40 parts in the several views.

The urinal 1 is of usual construction and preferably of porcelain or enameled iron. In a recess in the base, 1^a, an annular hollow ring, 2, of thin metal is placed; above this 45 ring is a strainer, 3. A pipe, 4, of small caliber, is connected to the ring, 2, and extends upwardly to the inner side of the diaphragm chamber, 5. A diaphragm 6, of suitable metal is held in position by the front 50 plate, 5^a, of the diaphragm chamber. A suit-

able washer, 7, with screw 7' is placed centrally on the diaphragm, connecting with and passing through another washer, 8, a plate 9, and a bushing, 10, the screw 7' projecting a short distance beyond the face of 55 the plate, 5^a, which is provided with an opening, 5^b, as shown. Below this opening two studs 5^c project, between which an L crank, 11, is pivotally mounted, a pin 12 acting as a journal. On the free end of this 60 crank an adjusting screw 13 is provided. A series of arms 5' are cast integral with the inner part of the diaphragm chamber, for fastening to a wall. The two plates forming the case for the diaphragm are secured 65 together by screws, 5^d, which also pass through the diaphragm and make an air and watertight joint. On the front plate, 5^a, an arm 5^d projects outward and another arm, 5^e, somewhat wider, extends down and outward for supporting the body of a valve case, 14, which is also provided with arms 14', 14^a for attachment by screws or otherwise. This valve is comprised of a case, 14, having a central longitudinal opening. A 70 valve seat 14^b is provided near the lower end, just above a side inlet 14^c for water: a side outlet 14^d is provided above the valve seat diametrically opposite the inlet opening. The valve, 15, has preferably a seat, 15', a 75 three-foiled body part 15^a, and a round extension 15^b which passes up through a bushing 16, which, with the body or case forms a stuffing box. Below the valve, a spiral spring, 17, pushes it upwardly against the 80 seat. A plug nut 18 closes up the lower opening. Coupling nuts 19, 20 are used to connect inlet and outlet pipes, respectively, 21, 22, with the body. The valve just described, and the flushing valve with which it 85 operates and which is described hereinafter are old and tried devices, and are made use of by me and described so as to show a complete working device, but other water flushing devices, operated by a plunger to open a valve initially, may be employed in connection with the ring and diaphragm construction first described and which is the essential feature of the invention.

The flushing valve is comprised of a cyl- 100

inder case body 23, having a side outlet 23' near the top, where a connection is provided with the pipe, 21, by means of a coupling nut 24. Below this side outlet and near the 5 lower end of the body is a water inlet 23² which connects with the supply pipe 25 for flushing the urinal. A coupling nut 26 fastens the pipe to the body. Diametrically opposite the water inlet, and just below it, is 10 an inlet 23³ to which the pipe 22 is connected by a coupling nut 27. On a line with the water inlet 23² a valve seat 23⁴ is produced upon which a floating valve, 28, rests. This valve is cup-shaped above the seat, the diameter being reduced below the cup and again below the seat, so that when the valve 15 is raised from its seat by the pressure of the water coming through the inlet pipe, 25, the perforated tail piece, 28', will permit the 20 free influx of the water. A small hole 28² is drilled in the cup to permit passage of a small quantity of water. The lower end 23⁵ of the valve body is threaded for connecting with the spray, 30, of the urinal, a pipe, 31, 25 connecting the two. The upper opening of the valve casing is also threaded for the reception of a cap nut 29 having a central stem 29' to limit the upward movement of the valve 28.

30 32 is a trap.

Such being the construction, the operation is as follows:—The ring, 2, pipe 4 and inner part of the diaphragm chamber 5 are completely filled with a fluid, either gaseous or 35 liquid, which quickly expands or contracts under the influence of a varying temperature, ether or spirituous alcohol may be employed. When all the water connections are made and the urinal is not in use, water will 40 be under pressure in pipe 25, valve body 23, pipe 21 to and under the valve 15 in body 14. The crank lever 11 is so adjusted that the 45 screw 7' on the diaphragm 6 contacts with the inner end while the screw 13 is adjusted so as to rest on the valve stem 15³ of the valve 15. When the urinal is in use, the liquid passes over the ring, 2, the fluid contained therein immediately begins to expand and continues such expansion until the diaphragm 6 is pushed outwardly, the flushing 50 mechanism is set in operation by the depression of the valve 15 which releases the water above the valve 28 causes it to raise from its seat and permit the influx of the flushing water through pipes 25 and 31, some of the water passing up through the hole 28² in the valve 28, and when the pressure above the valve 28 becomes greater than that of the water in pipe 25 (owing to the balancing of 60 the pressure plus weight of valve) the water supply is shut off, the colder water causing the fluid in the ring 2 to contract and the diaphragm to recede. For varying out door

temperatures the screw 13 is adjusted to suit conditions.

What I claim is:—

1. In combination with a urinal basin, a thermostatic member positioned therein, a flush valve, a diaphragm operatively controlled by said thermostatic member, actuating connection means between said diaphragm and valve whereby said valve is automatically operated upon the change in temperature of the thermostatic member. 65

2. In combination with a urinal basin, 70 of a thermostatic member positioned at the bottom thereof, a flush valve positioned adjacent the top of said basin, a diaphragm casing adjacent said flush valve, a fluid actuating diaphragm within said casing, operative communication between said thermostatic member and the interior of said casing and operative connections between said diaphragm and valve whereby said valve is 80 actuated upon a change of temperature. 85

3. In combination with a urinal basin, a thermostatic member positioned therein, a flush valve, a casing, a diaphragm within 90 said casing, fluid controlling means for said thermostatic member engaging said diaphragm and motion transmission means between said diaphragm and valve.

4. In combination with a basin, a thermostatic member within said basin, a casing, a diaphragm within said casing, a conduit between said thermostatic member and casing, a flush valve, operative connections between 95 said diaphragm and valve, and fluid within said thermostatic member adapted for actuating said diaphragm upon a change in 100 temperature within the basin.

5. In combination with a basin, a flush valve therefor, a thermostatically fluid controlled diaphragm adapted for movement upon a change of temperature within said 105 basin, operative connections between said diaphragm and valve, rocker means engaging said diaphragm, and an adjustable contact member carried by said rocker means and operatively engaging said valve. 110

6. In combination with a basin, a flush valve therefor, a diaphragm, operative connections between said diaphragm and valve, and means adapted for actuating said diaphragm upon a change in temperature with- 115 in the basin.

7. A device of the class described comprising a basin, a flush valve therefor, a diaphragm, means adapted for actuating said diaphragm upon a change in temperature 120 within the basin, rocker means engaging said diaphragm, and an adjustable contact means for said valve carried by said rocker means.

8. The combination with a urinal basin, 125 of a thermostatic member positioned there-

in, a flush valve adjacent said basin, a dia-
phragm casing, a fluid actuated diaphragm
within said casing, operative communica-
tion between said thermostatic member and
the interior of said casing, rocker means
engaging said diaphragm, and an adjustable
contact member carried by said rocker means
and operatively-engaging said valve.

Signed at New York city in the county
and State of New York this 27th day of 10
March A. D. 1913.

JAMES J. LAWLER.
